United States Patent Office

Des. 202,168
Patented Sept. 7, 1965

202,168

PLAY PEN

John W. Tapert, 2381 Earhart Road, Ann Arbor, Mich.

Filed Feb. 27, 1964, Ser. No. 78,796

Term of patent 14 years

(Cl. D5—5)

FIG. 1

FIG. 2

FIG. 3

5 3 5 = 4

The appearance of the panels not shown in FIG. 3 is the same as that of the panels shown.

I claim:

The ornamental design for a play pen, substantially, as shown and described.
